UNITED STATES PATENT OFFICE

1,994,705

APPARATUS FOR CASTING METALS

Charles C. Hill, Shaker Heights, and William M. Henry, Garfield Heights, Ohio, assignors to The American Steel and Wire Company of New Jersey, a corporation of New Jersey

Application May 2, 1933, Serial No. 669,052

2 Claims. (Cl. 22—57)

This invention relates to an apparatus for casting metals, and more particularly to casting ingots, although not limited thereto.

In the past, a number of attempts have been made to improve the quality of cast ingots by changing the characteristics of the metal. One method of procedure in the manufacture of certain grades of steel has been to employ expensive hot tops, the purpose being to prevent or reduce "piping" of the ingot. In other grades of steel, such as "rimmed" steel, gases and non-metallic inclusions are removed by ebullition and a shell or rim of substantial thickness is formed on the outside of the ingot. The results obtained from such a rimming action were not entirely satisfactory for the reason that the shell was of varying thickness, the bottom of the ingot having little or no such shell. It is desirable in making a superior "rimmed" steel that the shell or "rim" be of substantial thickness completely around the ingot from top to bottom.

Another line of procedure in attempting to obtain superior ingots has been to subject the mold to vertical vibrations in order to hasten particles of inclusions and gases to the surface of the liquid metal, it being a well known fact, of course, that the former are of considerably greater buoyancy than the steel and should rise to the surface of the latter if the steel can be held liquid for a sufficient length of time. However, due to the minuteness of the particles of inclusions and gases they do not rise to the surface with sufficient rapidity and are, accordingly, entrapped in the steel.

In accordance with the teaching of the present invention, the particles of inclusion and gases inherent in molten metal are made to come in contact with one another and coalesce to form larger particles, thus increasing their rate of rising to the top and preventing them from being entrapped and held by the pressure of the coagulating or solidifying metal.

One object of the present invention is the provision of a novel apparatus for obtaining an improvement in the quality of cast ingots.

Another object is the provision of means for coalescing particles of inclusions and gases inherent in molten metal, thereby enabling them to rise to the surface of the less buoyant metal.

Still another object is to provide a novel apparatus for procuring a highly satisfactory "rimming" action of molten metal by instituting convection currents therein, causing particles of inclusions and gases to come in contact with one another and coalesce to form larger particles,

thus increasing their rate of rising to the top of the metal.

A further object of the invention is to provide a novel means which may be conveniently employed during the entire time the molten metal is being "teemed" into conventional ingot molds, the addition to the mold of a "hot top" not being objectionable.

These and further objects will be apparent after referring to the drawings, in which:

Figure 1 is a side elevation of the apparatus of the invention.

Figure 2 is a plan thereof.

Figure 3 is a view on the line III—III of Figure 1.

Figure 4 is a sectional view of a detail of the invention.

Figure 5 is a view on the line V—V of Figure 4.

Referring more particularly to the drawings, the numeral 2 designates a platform which is disposed in a pit 3 in the "pouring floor", where molten metal is "teemed" from ladles into conventional ingot molds. The platform 2, which is of rectangular shape, rests upon springs 4 in such manner as to have its upper surface flush with the floor.

A pair of supports 5 are disposed at the bottom of the pit 3 and each adapted to carry a motor 6 which is provided with the usual driven shaft 6^a. The vibrators of the invention are disposed in housings 7, and each comprises a pair of anti-friction bearings 8 in which there is mounted a shaft 9 having an integral unbalanced weight 10 supported between the bearings.

A suitable flexible driving connection, indicated in the drawings at 12, is provided for connecting the driven shaft 6^a of each of the motors 6 to the rotary shaft 9 of each of the vibrators. The motors 6 may be of any conventional type, such as fluid or electric motors. The vibrator housings 7 are rigidly suspended from the platform 2 by means of supporting bars 14 connected to each of the vibrator housings 7 at one of their ends and to the platform 2 at their other ends.

A pair of track sections 15 are mounted on the upper surface of the platform 2 in order to enable the disposal thereon of a conventional ingot mold truck generally indicated at 16. In accordance with conventional practice, a pair of ingot mold stools 17 are carried on the truck 16 for supporting the usual ingot molds 18.

In order to insure that the action of the vibrators generally indicated at 7 will be transmitted to the ingot molds to a greater extent, if de-

sired, for certain kinds of steel, it may be essential that the molds 18, truck 16 and platform 2 be rigidly held together in a unitary manner. To obtain such rigidity of the apparatus, a plurality of ears 19 are provided on each of the ingot molds 18 and a plurality of corresponding ears 20 provided on the truck 16. A pair of rods 21, each of which is provided with an eyelet 21^a at one of its ends, are adapted to be connected to the ears by means of a pin 22 and are connected together by means of a conventional turnbuckle 23. Similar connections are provided for securing the truck 16 to the platform 2.

In operation, the motors 6 are suitably driven to rotate the shafts 9 of the adjacent vibrators through the flexible couplings 12. The rotation of the shafts 9 enables the integral unbalanced weights 10 to impart universal vibrations of small amplitude of both vertical and horizontal nature to the supporting bars 14, which are secured to the platform 2.

These vibrations, conveyed from the platform 2 to the ingot molds 18 through the truck 16, serve completely to coalesce the particles of inclusions and gases present in the molten metal in such manner as to assure the superior "rimming" action hereinbefore referred to.

While we have shown and described one specific embodiment of our invention, it will be understood that we do not wish to be limited exactly thereto, since various modifications may

be made without departing from the scope of our invention, as defined in the following claims.

We claim:

1. Apparatus for casting comprising a resiliently mounted platform adapted to support an ingot mold truck, means for rigidly securing at least one ingot mold to said truck, means for rigidly securing said truck to said resiliently mounted platform, at least a pair of independent vibrators secured to said platform, said vibrators each comprising an antifrictionally mounted rotary shaft carrying an integral unbalanced weight, a motor disposed adjacent each of said vibrators, and flexible driving connections between said motors and said rotary shafts. 5 10

2. Apparatus for casting comprising a resiliently mounted platform adapted to support an ingot mold truck, means for rigidly securing at least one ingot mold to said truck, means for rigidly securing said truck to said resiliently mounted platform, a frame rigidly secured to said resiliently mounted platform adjacent each of its ends, a vibrator connected to each of said frames, said vibrators each comprising an antifrictionally mounted rotary shaft carrying an integral unbalanced weight, a motor disposed adjacent each of said vibrators, and flexible driving connections between said motors and said rotary shafts. 15 20 25
